Patented July 26, 1921.

FIG. 1.

Inventor:
Henry M. Siegel
Chas. T. Randall
atty.

UNITED STATES PATENT OFFICE.

HENRY M. SIEGEL, OF MALDEN, MASSACHUSETTS.

HAIR-WAVER.

1,385,797.

Specification of Letters Patent. Patented July 26, 1921.

Application filed May 24, 1921. Serial No. 472,214.

To all whom it may concern:

Be it known that I, HENRY M. SIEGEL, a citizen of the United States, residing at Malden, in the county of Middlesex, State of Massachusetts, have invented a certain new and useful Improvement in Hair-Wavers, of which the following is a specification, reference being had therein to the accompanying drawings.

10 My invention is a novel and improved means for imparting to the hair of the human head a series of transverse bends or undulations, on the order of that commonly known as a "Marcel wave." One purpose of 15 my invention is to enable the user to impart such undulations without the use of a curling iron, or other application of heat, which tends to injure the quality of the hair and involves the risk of serious damage thereto. 20 Other objects are to enable the user to wave hair successfully even though not possessed of the high degree of skill and manual dexterity required for successful use of heated appliances, and without the assistance of 25 another person; and also to leave the user's hands free for other employment during the time while the said bends or undulations are impressing themselves upon the hair, or, as it is usually expressed, while the wave is 30 becoming set.

My invention consists in a hair waving device comprising a body portion, a transverse series of teeth at one end thereof to engage a lock of hair adjacent the scalp, a 35 double series of oppositely-disposed cleats about which the hair may be looped in sinuous manner in an alternating succession, and a retaining finger at the other end to retain the free end of said lock of hair.

40 An illustrative embodiment of the invention is shown in the accompanying drawings, in which,—

Figure 1 illustrates a head with the invention applied as in use.

45 Fig. 2 is a plan view of the device.

Fig. 3 is a side view thereof.

Fig. 4 is a view in cross section on line 4, 4, of Fig. 2.

Having reference to the drawings,—

50 While a device embodying the invention may be molded or cast as a whole from metal or composition, or made from separate component parts united in any well known manner, the preferred construction as regards economy of labor and material, and for lightness, is to form the article from a single

piece of sheet celluloid, metal, or other approved material, cut out, stamped and pressed into the desired conformation.

The transverse row of teeth 1^a, 1^a, 1^b, provided at one end of the device is adapted to be entered into the lock of hair that is to be waved, at the root-ends of the hairs, closely adjacent the user's scalp. The extremities or points of these teeth extend inward toward the other end of the body-portion 2. The terminal tooth 1^b at one end of the series, adjacent the first cleat, 4, at one side of the device, is made larger than the others in order to render it somewhat stiffer and stronger, its free extremity being bent toward the surface of the body of the device, in order to retain in place under the same more effectually the portion of the lock which extends from the comb-teeth to said 75 cleat. To facilitate the introduction of the lock under the said tooth or finger, the said free extremity thereof is somewhat recurved away from the said surface. This finger or tooth serves to hold in a more or less compact strand the portion of the hair which extends from the said teeth to the first cleat. The side of said heavier tooth or finger 1^b toward said first cleat 4 is cut away to accommodate the hair between the said side 80 and the upstanding portion of the cleat.

The lock of hair having been dampened with water or any other suitable medium, if necessary, it is wound tightly in undulating or zigzag manner around cleat 4, thence 90 across the body-portion to the first cleat, 5, located upon the opposite lateral edge of the body-portion, around said cleat 5 and back across the body-portion to the second cleat 4, and so on throughout the length of the appliance. At the other end of the appliance the lock is held fast by passing it under the retaining finger or clasp 7 at such end of the body-portion, and by wrapping it around the said finger or clasp one or more times. 100 The body-portion 2 is preferably concaved longitudinally on its under side, to conform to the user's head. The device is left in place until the hair dries, and as much longer as is practicable, as the lasting 105 qualities of the wave are in direct proportion to the length of time the undulations are allowed to set, or remain undisturbed upon the device. Thereupon the end of the lock of hair is disengaged from the retaining finger or clasp 7, and the lock is unwound from the cleats back to comb 1^a, 1^a, 1^b, whereupon the 110

latter will be free to disengage from the hair.

The cleats 4, 4, 5, 5, preferably are arranged in the alternate or zigzag relation shown in the drawings, but are not necessarily so disposed. They may be located opposite or abreast of each other across the body-portion 2. For this manner of winding the hair on, the cleats are constructed by forming the material of which the device is composed into semicircular lateral projections having upstanding flanges 4^a, 4^a, 5^a, 5^a, and outstanding lips 4^b, 4^b, 5^b, 5^b. Preferably, also, tongues 4^c, 4^c, parallel with the lips 4^b, 4^b, and spaced therefrom by the height of the upstanding flanges 4^a, 4^a, are provided by punching narrow portions out of the said semicircular lateral projections and bending these tongues to extend outward in approximately the plane of the body-portion 2 to a distance equal to the projection of the lips 4^b outward from the body-portion.

The length of my device, and consequently the number of cleats in the length of the series, is determined by the length of the portion of one's hair which it is desired to wave.

I claim as my invention,—

1. A hair-waving device comprising a body-portion provided with a double series of cleats adapted to have a lock of hair wound sinuously back and forth around the same in an alternating succession, for forming a series of undulations or waves in said lock, a comb at one end of said body-portion adapted to be engaged in said lock at or adjacent the root-ends of the hairs, and a lock-retaining finger at the opposite end thereof.

2. A hair-waving device comprising a body-portion, a transverse series of teeth at one end of said body-portion, a double series of cleats thereon, and a lock-retaining finger at the other end thereof.

3. A hair-waving device comprising a double series of cleats adapted to have a lock of hair wound sinuously back and forth around the cleats in an alternating succession, a transverse series of inwardly facing comb teeth at one end thereof adapted to be entered into said lock at its root-end, one of said teeth enlarged and shaped to clasp the lock of hair between the comb and the adjoining cleat, and a lock-retaining finger at the opposite end of the device.

4. A hair-waving device comprising a body-portion, a transverse series of teeth at one end thereof having their free extremities extending toward the center of the said body-portion, oppositely disposed cleats upon the body-portion arranged in alternate or staggered relation, and a lock-retaining finger at the other end of the body-portion.

5. A hair-waving device comprising a body-portion, curved longitudinally to conform to the contour of the human head, a double series of upstanding cleats thereon, a transverse series of comb teeth at one end of said body-portion, and a hair-retaining finger at the other end thereof.

In testimony whereof I affix my signature in presence of two witnesses.

HENRY M. SIEGEL.
